UNITED STATES PATENT OFFICE

163,245

FILM MATERIAL OR LIKE FLAT SURFACE
MATERIAL

John Bolten, Sr., Andover, Mass.

Application November 28, 1950, Serial No. 13,164

Term of patent 14 years

(Cl. D92—1)

To all whom it may concern:

Be it known that I, John Bolten, Sr., a citizen of the United States, residing in the city of Andover, county of Essex, State of Massachusetts, have invented a new, original, and ornamental Design for Film Material, or Like Flat Surface Material, of which the following is a specification, reference being had to the accompanying drawing, forming part thereof.

On the drawing, the figure is a plan view of a film material, or like flat surface material, showing my design.

Substantially a design unit is outlined by dot-and-dash lines, and said unit is repeated as indicated by the extensions beyond the unit boundary.

The ground shading has been omitted from the material beyond the design unit for convenience of illustration.

I claim:

The ornamental design for a film material, or like flat surface material, substantially as shown and described.

JOHN BOLTEN.
